UNITED STATES PATENT OFFICE

ANDREW THOMPSON, OF NIAGARA FALLS, NEW YORK, ASSIGNOR TO THE EMBOSSED COMPANY, OF ALBANY, NEW YORK, A CORPORATION OF NEW YORK

SIGNBOARD OUTFIT

Application filed September 16, 1931. Serial No. 563,010.

This invention relates to signboards or display outfits having letters and other characters which may be variously arranged so that different spacings of the letters and words may be had in accordance with the needs of any particular signboard.

My invention involves the use of letter blocks which are provided with a plurality of projections for affixing the same to a board having recesses therein. The recesses are separated by two series of raised strips, one series of strips being angularly related to the other and intersecting the same whereby a plurality of polygonal recesses are formed intermediate the strips. There are a plurality of projections on the under side of each letter block and these are so proportioned as to engage the four bordering strips of a single recess or the intersecting strips between four recesses or both sides of a single horizontal strip between two recesses or both sides of a single vertical strip between two recesses, thus providing a plurality of possible positions of a single block for each grouping of four recesses, the number of such positions being dependent upon the number of projections which each block has. The recesses in the board enable the accurate alignment of words which are made up by the individual letter blocks.

The size of a letter block is such that the edges of adjacent letter blocks abut when the blocks are held by adjacent recesses, and words may be spaced or the spacing of letters may be increased fractionally depending upon the number of projections on the under side of a block: thus, two projections in line will enable half spacing, three projections in line enable spacings in thirds, four projections in line enable spacings in quarters, etc. While any one of different fractional spacings may be used, it will suffice to disclose the principle of my invention by reference to letter blocks enabling half spacing.

Referring to the drawings:—

Fig. 1 is a plan of the signboard outfit with wording appearing thereon.

Fig. 2 is a section on line 2—2 of Fig. 1.

Fig. 3 is a perspective view of a letter block showing its upper side.

Fig. 4 is a perspective view of a letter block showing its under side.

Fig. 5 is a diagrammatic showing of the manner in which the spacing and placing of letters and words may be varied.

The signboard outfit illustrated in Figs. 1 and 2 includes a base or background 9 having a multiplicity of rectangular recesses 10 arranged in horizontal and vertical alignment. These recesses are defined by a series 60 of horizontal strips 11 and a series of vertical strips 12 which extend throughout the surface of the base or background.

Ordinarily it is preferable to mount the base within a box similar to that shown in Figs. 1 and 2. This box has a bottom 13 to which the board is attached, and a cover 14, hinged to the bottom 13, carries a cover glass 15 through which the sign may be viewed. Since signs are usually mounted in a vertical position, it is desirable to keep the letter blocks from shifting their positions and for this purpose the cover glass is so positioned as to extend over the tops of the letter blocks.

The letter blocks, of which one is shown in Figs. 3 and 4, are of the same shape as the rectangular recesses in the base, in the present instance square, and their area is such as to contact their edges when adjacent blocks are similarly secured in the base. The upper sides of the latter blocks carry letters, preferably embossed and contrastingly colored on top, as shown in Fig. 3, and some may bear different indicia as well as punctuation marks. The under side of each letter block has four projections as illustrated in Fig. 4. These projections are so spaced in respect to one another that the projections in a vertical line may lie at opposite sides of a horizontal strip 11 and the projections in a horizontal line may lie at opposite sides of a vertical strip 12. As may be understood from Fig. 5, the projections 17, 18, 19 and 20 are so proportioned as to snugly engage a single recess 10 or a single horizontal strip 11 or a single vertical strip 12, or both a horizontal and vertical strip, as illustrated by the letter blocks 21, 22, 23 and 24, respectively.

The letter blocks may be made in any manner which is productive of a smooth sur-

face and attractive lettering. In view of the excellent results that may be obtained by embossing, I prefer to use this method and the blocks may be made by the embossing process described in the patent of Charles M. Hyatt No. 1,322,792, issued November 25, 1919. In this process a wooden blank, cut with the grain perpendicular to the square faces is forced down into a tubular die by means of an upper plunger die which forces the blank with great pressure upon a lower die at the bottom. The side walls of the tubular die compress the wood radially inwardly and impart a high finish to the sides of the block and the upper and lower dies 10 shape and impart a high finish to the faces of the block. The operation is rapid and uniform in results and has the further advantage that the powerful compression of the wood strengthens the blank very substantially. With a rather tough wood, for example, well seasoned maple, the additional strength imparted by the compression insures virtually complete freedom from 20 breakage of even thin letter blocks, in spite of the fact that they are made "endwise" of the grain.

In use the letter blocks are selected to make up the desired wording for the sign. 30 Having reference to Fig. 1, it will be noticed that the word "Notice" appears at the head of the sign. The letters in this word are held in place by the projections straddling the vertical strips 12. A dash appears at either 35 end of the word. This dash is spaced one-half a letter from the end of the word and the projections of the dash block engage the inner edges of the strips of a single recess. The word "Notice" appears as a caption and 40 the first line of the remaining words of the sign is spaced one full line space below. It is apparent that this spacing may be any multiple of a half-letter spacing. Each of the letters appearing in the line bearing the 45 words "This sign is" is bisected by a single strip 12, and the spacing of the words is one full letter space.

Each of the letters of the word "Flexible" 50 is directly above intersecting horizontal and vertical strips and the projections engage these strips in the manner illustrated by letter block 24 in Fig. 5. The words of the line of words "It can be used" are so positioned as to balance the line with the second line 55 "This sign is", and this is made possible by varying the spacing at either side of the word "Be". The letter blocks of the line "Many ways" are affixed to the base in a manner similar to the letter block 22 in 60 Fig. 5. It is proposed to finish the projections and the recesses in such a manner as to have uniformity in dimensions, and because of this all of the letter blocks will snugly engage the strips and recesses in the base 65 howsoever placed in respect thereto.

In the interest of convenience, a base of an appropriate size similar to the base of the sign may be provided as a letterholder or rack for the letter blocks which are not in use.

It is apparent that while I have shown the strips in the base intersecting each other at right angles, a different angular relation of these strips is possible and I do not desire it to be understood that the invention is limited to the form herein specifically described for 70 it is apparent that it is susceptible of embodiment in other forms without departing from the spirit of the invention and coming within the scope of the claims which follow.

I claim:

1. A letter block for a sign outfit comprising a board having a plurality of square recesses which are separated by raised strips and letter blocks to be engaged by said strips, said block having four projections on its under surface arranged in a square whose dimensions correspond with those of a recess, the projections being spaced from each other a distance corresponding to the width of the 80 raised strips on the board.

2. A sign outfit comprising a board having a plurality of polygonal recesses separated by two series of strips, the strips in one series being parallel to each other and running at an angle to the strips of the other series, and a plurality of letter blocks, each having a letter on its upper surface and a plurality of projections on its lower surface, said projections being arranged to fit within a single recess in the board when in one position on the board or to blank both sides of a strip when the block is in another position on the board. 90

3. A sign outfit comprising a board background having a plurality of polygonal recesses separated by two series of strips, the strips in one series being parallel to each other and running in a direction at right angles with the strips of the other series, a plurality of letter blocks, each having a letter on its upper surface and a plurality of projections on its lower surface for engaging the sides of any one strip or of two adjacent strips depending upon the position of the letter block upon the board and means for holding the letter blocks in predetermined positions with their projections engaging the strips of said board. 100

4. The combination set forth in claim 3 in which the means for holding the letter blocks in predetermined positions comprises the glass cover of a box which overlies the surface of the board. 110

5. In combination, a base for supporting letter blocks, said base having in its upper surface a plurality of uniformly disposed recesses separated by strips, and a plurality of letter blocks adapted to be located in different positions in respect to said strips, each of said letter blocks having on its under side a plurality of projections so spaced that ad- 120 125 130

jacent projections may be disposed in recesses on the opposite sides of a strip or in a single recess, depending upon the position it is desired that the block remain in respect to the 5 surface of the base.

6. In combination, a base for supporting letter blocks, said base having in its upper surface two series of raised strips, at right angles to each other and forming a plurality 10 of rectangular recesses in the base, and letter blocks arrangeable in different positions upon said base, each of said blocks being provided on its under side with a plurality of projections so proportioned as to lie within 15 a single recess of the base or at opposite sides of a single strip, depending upon the position it is desired that the block remain in respect to the surface of the base.

In testimony whereof I hereto affix my 20 signature.

ANDREW THOMPSON.
